UNITED STATES PATENT OFFICE

OTTO J. GROEHN, OF GROSSE POINTE PARK, AND LAWRENCE S. LAMB, OF GROSSE POINTE, MICHIGAN, ASSIGNEES TO HUDSON MOTOR CAR COMPANY, OF DETROIT, MICHIGAN, A CORPORATION OF MICHIGAN

APPARATUS FOR SHAPING SHEET METAL

Original application filed December 28, 1927, Serial No. 243,030, Patent No. 1,708,615, dated April 9, 1929. Divided and this application filed February 8, 1929. Serial No. 338,468.

This invention relates to apparatus for shaping sheet metal and more particularly to apparatus for shaping a strip of sheet metal to polygonal form so as to bring the free ends of the strip together.

5 This application is a division of our pending application, Serial No. 243,030, filed December 28, 1927, Patent No. 1,708,615, dated April 9, 1929, which discloses a 10 method of shaping sheet metal to produce a quarter window finish molding for an automobile body.

It is the object of the present invention to provide an apparatus of simple construction in which a strip of sheet metal may be shaped easily to polygonal form so as to bring the free ends of the strip together.

The invention will be more clearly understood from the following description in conjunction with the accompanying drawings: 20 in which,

Fig. 1 is a plan view of an apparatus embodying the invention;

Fig. 2 is a detail view of a detachable portion of the same;

25 Figs. 3 and 4 are fragmentary elevational views of portions of the apparatus showing the permanently and detachably mounted devices respectively for shaping the blank around the supports for defining the vertices of the polygon; and

Fig. 5 is a plan view of the blank as shaped with the apparatus.

Before explaining in detail the present invention, it is to be understood that the invention is not limited in its application to the details of construction and arrangement of parts illustrated in the accompanying drawings, since the invention is capable of 30 other embodiments and of being practiced or carried out in various ways. Also it is to be understood that the phraseology or terminology employed herein is for the purpose of description and not of limitation, and it 35 is not intended to limit the invention beyond the terms of the several claims hereto appended as considered in view of the prior art and the requirements thereof.

One form of apparatus embodying the invention and which is adapted particularly

for shaping a strip of sheet metal to the polygonal form of a window opening is shown in the drawings and comprises a table 15 having pins 16 mounted therein upon which suitable supports 17, such as rolls, 55 are pivotally mounted, and which are positioned to define two adjacent vertices of the polygon. In the form illustrated the rolls 17 are mounted upon the pins 16 between a lever 18, pivotally mounted upon the pins 16 adjacent the top surface of the table, and brackets 19 extending from near the top of the pins 16 to the table and secured to the latter in any suitable manner, as by bolts 20. A roll 21 is pivotally mounted upon a stud 60 22 on each lever 18 and is positioned to engage the body of the strip of sheet metal and shape the same against the corresponding support or roll 17.

The supports defining the other vertices 70 of the polygon may conveniently be in the form of rolls 25 pivotally mounted upon pins 26 mounted in plates 27 which are secured to the top surface of the table in any suitable manner, as by bolts 28. A detachable manually operated device, such as a 75 lever 29, is provided with a notch 14 for detachably and pivotally connecting the lever to the pins 26. The levers 29 are provided with studs 30 carrying rolls 31 positioned to 80 engage the body of the strip of sheet metal and shape the same about the rolls 26. In order that the strip of sheet metal may be elevated to a suitable position relative to the rolls 17 and 25, the table is provided with 85 suitable upwardly extending projections 32 which engage and support the strip of sheet metal between the supports or rolls defining the vertices of the polygon.

In shaping the strip of sheet metal the 90 outer surface of the body of the sheet metal adjacent the central flanges is positioned to extend between and against the rolls 17 and with rolls 21 against the inner surface of the body of the sheet metal. The strip of sheet metal is then bent manually at right angles around each of the rolls 17 and thereafter the levers 18 are manually operated in the direction of the arrows (Fig. 1) to bring 95 the rolls 21 against the body of the strip of 100

sheet metal and shape the same around the rolls 17. The strip of sheet metal is then bent at right angles around each of the rolls 25 to bring the free ends together. The 5 levers 29 are then mounted upon the pins 26 so as to bring the rolls 31 into engagement with the body of the strip of sheet metal which then is shaped around the rolls 25 by turning the levers 29 in the direction 10 of the arrows (Fig. 1).

We claim:

In an apparatus for bending a strip of sheet metal substantially to the shape of a polygon, the combination of a support defining each vertex of the polygon, a permanently pivotally mounted device for shaping the sheet metal around two adjacent supports, and a detachable manually operated device including a roll adapted to engage 20 and shape the sheet metal around the other supports.

In testimony whereof we affix our signatures.
